UNITED STATES PATENT OFFICE.

WALTER A. FRANTZ, OF CLEVELAND, OHIO.

CLOTHES WRINGER.

Refiled for abandoned application Serial No. 577,120, filed July 24, 1922. This application filed June 23, 1924. Serial No. 721,630.

This application is filed to take the place of the application of Walter A. Frantz, Serial No. 577,120, and filed July 24, 1922, which application was abandoned prior to 5 the filing of this application.

This invention relates to clothes wringers, especially those of the type used with power driven washing machines and has for its general object the provision of a new and 10 improved guide for conveying the clothes to and from the wringer combined with a drip board whereby the expressed water is returned to the tub or casing. In machines of this character the opening in the washing member through which the clothes are 15 drawn or into which they are admitted is frequently a considerable distance from the plane of the wringer and the receptacle to which the wringer delivers the clothes is 20 also frequently placed at some distance. This necessitates the use of a chute upon both sides of the wringer, which chute is preferably made symmetrical on the two sides inasmuch as the wringer is generally 25 pivoted on a vertical axis and operable in either direction so as to approach the washing member from either side. The great width of the chute renders it desirable that the expressed water be returned to the tub 30 by some independent channel so far as possible; and the reversible character of the wringer renders it necessary to provide for the reversal of the drip. All these conditions are met by my improvements along 35 with many others which will appear as this description proceeds.

In the drawings accompanying and forming a part of this application I have shown one of the physical forms in which my invention can be embodied although it will be understood that these drawings are intended to be merely illustrative and not limiting upon me. Fig. 1 is a vertical section through a combined washing and wringing machine equipped with my invention; Fig. 2 is a side elevation of the parts shown in Fig. 1; Fig. 3 is a perspective view of a part of one end of my attachment.

Describing the parts by reference characters, 1 represents the casing of a washing machine and 2 the clothes-receptacle therein which may be of the rotating, oscillating, reciprocating, or any other type whatever. Generally the opening 3 through which the clothes are inserted and removed is located

at some little horizontal distance from the casing wall, and in the present case I have shown this opening as provided with a removable cover 3^a, though with some types of clothes receptacles no cover is employed. 60 The wringer consists of a frame 4 mounted upon a bracket 5 to swing about a vertical axis coinciding approximately with one side of the casing and having rolls 6, 6 adapted to be driven in either direction by suitable 65 gearing contained in the gear box 7 and controlled by the clutch lever 8. With this arrangement the wringer can be located over either side wall of the casing and locked by a suitable catch 9. 70

To the bottom of the wringer frame my improved attachment is secured, the same comprising a pair of end members 12, notched at 13 to receive the frame and connected at opposite sides of the notches by 75 flat inclined plates 14 of sufficient width substantially to bridge the gap between the casing 1 and the opening 3. As a result of the lateral extent of these plates and of the desirability of keeping the wringer as 80 low as possible, the angle of these plates with the horizontal is made comparatively small, say about 30° more or less but seldom as much as 40°. The end members are continued above these plates to form guides 15, 85 this defining clothes chutes to and from the wringer rolls.

The bottom part of the frame 4 is left open for the escape of expressed liquid and between the end members 12, 12 is pivoted 90 a drip board 16 whose width is nearly as great as that of the plates 14, 14. At its inner end this board projects sufficiently beyond the frame opening to catch all the drip and is bounded upon three margins 95 with a flange 17 projecting at each side to arrest splashing and guide the water back to the casing. Its margin is also provided with a knob 18 by which it can be turned, the end members being formed with notches 100 19 for reception of the knob. I have shown the pivot pin as provided with a thumb nut 20 to hold the drip board in place.

With this device the wringer can be located on either side of the clothes receptacle 105 and run in either direction, lifting the clothes directly out of the receptacle and delivering the same well away from the casing, while the adjustable pivoted drip board enables the drip to be discharged at any 110

2

point without changing the position of any other part. The drip board constitutes the bottom of the entire mechanism and being freely pivoted permits the removal of any small articles which may accidentally drop through the wringer frame as well as enabling easy cleaning.

Having thus described my invention what I claim is:

- 10 1. In laundry apparatus the combination with a casing, a wringer frame pivoted thereto upon a vertical axis located outside said casing and a clothes receptacle located inside said casing and having a mouth therein spaced from the casing wall, of a clothes guide rigidly attached to said frame and comprising an outwardly and downwardly inclined plate extending at each side of the frame from a point adjacent the rolls to a distance approximately sufficient to bridge the gap between the casing and the mouth of said clothes receptacle, and a drip board pivoted upon a horizontal axis beneath said rolls and adapted to direct the drip to one side or the other of said wringer frame.
- 15 2. In a laundry apparatus, the combination, with a casing, a wringer frame mounted with its plane substantially in the plane of the side of the casing, and a clothes receptacle located inside said casing with its

opening spaced from the side wall thereof, of a clothes guide rigidly attached to said frame and projecting symmetrically on both sides thereof a distance approximately 35 equal to the horizontal distance between said side wall and said opening, each guide having a slanting bottom and an upright end wall, said wringer frame having an opening between said guides, and a reversible drip 40 board located below said opening and extending from a position at one side of said opening to a point near the tip of the opposite guide.

3. An article of manufacture comprising 45 a pair of spaced upright end members having notches for the wringer frame and flanges projecting above said notches to form guides, a pair of bottom plates connecting said end members, one on each side 50 of said notches and slanting away therefrom, the adjacent margins of said plates being spaced apart, and a drip plate pivoted between said end members on a horizontal axis lying below said notches, said drip 55 plate extending from the margin of one plate substantially to the tip of the other plate.

In testimony whereof, I hereunto affix my signature.

WALTER A. FRANTZ.
